UNITED STATES PATENT OFFICE.

JOHN JAMES ABELL AND CLARENCE BEN GIFFORD, OF COLESBURG, KY.

PENDULUM FOR ELECTRIC CLOCKS.

SPECIFICATION forming part of Letters Patent No. 351,239, dated October 19, 1886.

Application filed August 4, 1886. Serial No. 210,009. (No model.)

To all whom it may concern:

Be it known that we, JOHN JAMES ABELL and CLARENCE BEN GIFFORD, citizens of the United States, residing at Colesburg, in the

5 county of Hardin and State of Kentucky, have invented a new and useful Improvement in Pendulums for Electric Clocks and Means for Oscillating the Same, of which the following is a specification.

10 Our invention relates to an improvement in pendulums for electric clocks and means for oscillating the same; and the object of our invention is to provide a mechanism for oscillating the pendulum of an electric clock or system of electric clocks.

15 A further object of our invention is to provide a compensating mechanism for the pendulum, to prevent variations in temperature from affecting the accuracy of the time mechanism; and a further object of our invention is to provide a regulator for the pendulum, by means of which the latter may be adjusted.

To these ends our invention consists in the peculiar construction and combination of devices, that will be more fully set forth hereinafter, and particularly pointed out in the claims.

In the drawings, Figure 1 is a front elevation of an apparatus embodying our improvements. Fig. 2 is a side elevation of the same. Fig. 3 is a top plan view, portions of the supporting - plate being broken away so as to disclose subjacent mechanism. Fig. 4 is a bottom plan view. Figs. 5, 6, and 7 are detailed views. Fig. 8 is a diagram in which the circuits are traced.

A represents the case in which the mechanism is inclosed. In the upper portion of this case are secured brackets B, which support a 40 horizontal metallic plate, C. On the lower side of the plate is secured a horseshoe electro-magnet, D, by means of a threaded stem, E, which depends from the plate and passes between the coils, and a yoke which bears under the coils, and through which the stem passes, the said yoke being clamped under the coils by a thumb-nut, T, which works on the lower threaded end of the stem.

45 G represents a bracket which depends from the lower side of the plate, and has at its lower end a horizontal outwardly-extending arm, g.

Vertical bearing-screws H extend through the plate and through the arm g, with their points toward each other, the said screws being in a line with each other.

55

I represents an armature having at its inner end a pivot-arm, i, the ends of which are pointed and have their bearings in depressions or recesses made in the points of the set-screws H. The armature is in proximity to the poles of the electro-magnet, and its vibrations are limited by the adjusting-screws K, which approach on opposite sides and pass through the vertical arms of a yoke, L, that depends from the outer side of the plate C.

65

The outer end of the armature I, which projects beyond the front edge of the plate, has a right-angled horizontal arm, M. A hard-rubber or other suitable non-conducting plate, M', depends from the arm M. To one side of the 70 said plate is attached a vertical plate or strip, N, made of conducting metal, and to the opposite side of the plate M' is attached a similar plate or strip, O, which is also made of conducting metal. The lower end of the conducting-plate N has a contact-point, N', made of platinum wire, and the plate O has a similar contact-point, O', the said points N' and O' extending toward each other. A conducting-wire coil, N², connects the plate N with a 75 binding-post, P, that is attached to the plate C, and insulated therefrom, and a conducting-wire coil, O², connects the plate O with a binding-post, R, that is also attached to the plate C, and is insulated therefrom. From the lower side of the plate C depends a stud, S, forming the bearing for a thumb-screw or drum, S', to which is attached one end of a coiled tension-spring, S², the other end of the said spring being attached to the armature.

90

T represents a supporting-arm which extends outwardly from the front side of the plate C. The outer end of this arm is recessed or cut away on one side, and in the said cut-away portion is placed a jaw, T¹, which 95 is secured to the arm by a screw, T². From one side of the outer end of the jaw T¹ projects a dowel-pin, T³, which enters an opening in the opposing face of the arm T.

V represents an arm which projects from the front side of the plate and rests against one side of the arm T. This arm V has at its

outer end a right-angled extension or arm, V', which extends across the outer end of arm T, at a suitable distance therefrom.

W represents a vibrating arm or crutch-wire, having its upper end pivoted between the inner side of the arm V' and the front end of the arm T, directly in line with the center of the latter and with the center of the plate C. The lower end of the vibrating arm has a fork or yoke, W', which extends rearwardly. This arm W has near its upper end a contact-spring, W², made of thin sheet-steel, and provided at its upper end with a forwardly-extending arm of platinum wire, W³, forming a contact-point, which extends outwardly between the contact-points N' and O'. When the vibrating arm is in an exactly vertical position, the point W³ is out of contact with both the points N' and O'.

X represents a flat spring-leaf, which has its upper portion secured between the arm T' and its jaw T¹, so that the leaf is prevented from vibrating laterally, but is free to be adjusted up and down. The upper end of the leaf is pivoted in the bifurcated lower end of an adjusting-screw, X', and the lower end of the leaf has a block, X², in which is made a forwardly and upwardly extending open slot, X³. The upper end of the spring-leaf is pivoted to the lower end of the adjusting-screw, in order to permit it to swing slightly back or forth with the pendulum in the event that the clock-case is not in a perfectly vertical position. The lower portion of the screw X', which extends below a lever, to be hereinafter described, is provided with a scale, the degrees of which correspond with the pitch of the screw-threads.

Y represents a slotted link, that has its lower end pivoted to a stud, which projects from the upper side of the plate C, at the center and rear side of the latter.

From the lower side of the plate C depends a pair of iron rods, a, connected at their lower ends by a horizontal bar, b, the said rods and bar forming a stirrup.

c represents a brass rod, which has its lower end stepped in a central recess made in the upper side of the bar b. The upper portion of the brass rod c passes through an opening in the center of the plate C, and the extreme upper end of the said rod c is bifurcated.

d represents a supporting-lever of the third class, which has its rear end secured in the slotted link Y. At the center of the lever are trunnions e, which bear in semicircular recesses in the upper bifurcated ends of the brass rod, whereby the said lever has its center fulcrumed on the upper end of the brass rod. The outer or front end of the lever has a head, f, provided with a vertical opening, h, to receive the unthreaded portion of the screw X'.

An annular nut, k, which is graduated into ten numbered spaces, each of which is subdivided into tenths, works on the upper threaded portion of the screw X', and bears upon the upper end of the lever d. At the front end of the latter is a pointer, l.

m represents the pendulum-rod, which is made of iron and has its upper end provided with an open vertical slot, through which extends a transverse pin, n. The pendulum-bob o is firmly secured to the lower end of the rod by a screw, p. The pendulum-rod is attached to the lower end of the spring-leaf by inserting the block X² of the latter in the slot at the upper end of the pendulum-rod, and causing the pin n of the rod to engage the slot in the block. The fork or yoke of the vibrating arm engages the pendulum-rod, so that the pendulum and the vibrating arm are caused to oscillate together.

The plate C is provided on its lower side with an insulated binding-post, r, which is connected to one terminal of the coils of the electro-magnet, and with a similar insulated binding-post, s, which is connected to the opposite terminal of the coils of the electro-magnet. A binding-post, t, is on the upper side of the plate C, and is connected electrically therewith. In order to insure electric connection between the vibrating arm and the plate C, we connect the upper end of the vibrating arm with the arm V by a conducting-wire coil, U.

On the lower side of the inclosing case is a compartment in which is located a galvanic battery, which usually consists of only one cell. The compartment is large enough to receive two cells. On one side of the case is an insulated conducting-wire, v, having its upper end connected to the binding-post t, and its lower end connected to one pole of the battery. The lower end of the wire v has a free branch or terminal, v'. In the opposite side of the inclosing-case is another conducting-wire, w, the upper end of which is connected to the binding-post s' on the upper side of the plate C, and the lower end is connected to the remaining pole of the battery. From the lower end of the wire w extends a free branch or terminal wire, w'. The wires v and w, the plate C, and the arm V form the local circuit. When the battery needs replenishing, a new one is connected to the terminal wires w' and v' before the one in use is removed, and thus the electric current is not interrupted. In the top of the case are two binding-posts, x and y. A conducting-wire, x', leads from the post x to the binding-post R, and a conducting-wire, y', leads from the post y to the post s'. The line-wires z are attached to the posts x and y, and form a line-circuit in which is included the electro-magnet of an electric clock, z', or a system of such clocks, which is not more particularly described, as it may be of the ordinary form, and forms no part of this present invention.

The vibrating arm forms a switch.

The operation of our invention is as follows: When the pendulum is at rest, the point W³ is out of contact with both the points N' and O', and consequently both the local and the line circuits are broken. In order to start the apparatus the pendulum is swung to the left, so

as to cause the point W^3 to contact with the point N' , thus closing the local circuit, and causing the current from the battery to pass through the coils of the electro-magnet D, 5 and thus magnetize the cores thereof and cause them to attract the armature. This movement of the armature causes the point N' to bear upon the point W^3 at the free end of the spring W^2 with sufficient power to impart 10 a slight impulse to the pendulum when it reaches the limit of its movement to the left, and it then swings to the right, causing the local circuit to be broken by breaking contact between the points N' and W^3 , thus in- 15stantly demagnetizing the electro-magnet D, and the tension-spring then moves the armature to the left while the pendulum is swinging to the right, and causes the points O' and W^3 to contact, thus establishing the line-cir- 20cuit, and causing a current to traverse the line-wires to the electro-magnets in the clock or system of clocks in the circuit, to actuate the same. The pendulum is thus impelled in one direction by the attraction of the electro-mag- 25net on the armature, and in the opposite di- 30rection while the local circuit is broken by the action of the tension-spring.

From the foregoing description it will be readily understood that we employ only one battery to operate both the local and the line circuits.

The iron rods which depend from the plate C and carry the cross-bar forming the stirrup, and the brass rod, which has its lower 35 end stepped in the stirrup and its upper end attached to the lever from which the pendulum is suspended, form a compensating or automatic regulating apparatus, to counteract the effects of contraction and expansion of the 40 pendulum-rod under variations of temperature. If the pendulum-rod be heated a cer- 45tain number of degrees, it will expand a cer- 50tain distance, and the iron rods will also expand at the same time and in the same direction. The brass rod, which expands farther under the same temperature than the iron rods, moves upwardly against the suspending lever-arm and raises the center of the same through a space equal to the excess of the expansion 55 of the brass rod over the expansion of the iron rods and the lever-arm, and consequently the 60pendulum, which is suspended from the outer extremity of the lever, will be raised through a space equal to twice this excess. If, then, the length of the brass rod be such that its ex- 65cess of expansion is one-half the expansion of the pendulum-rod, including the leaf X, this brass rod will automatically raise or lower the pendulum just as much as the pendulum-rod and leaf may expand or contract under the in- 70fluence of heat or cold.

To determine accurately the length of brass rod necessary to compensate a pendulum of any given length the following formula is used:

$$65 B = \frac{1}{2} \times \frac{L \times i}{b - i}, \text{ or } B = 0.924 L, \text{ approximately,}$$

where B is the required length of brass rod.

L is the length of pendulum-rod and leaf to be compensated. i is coefficient of the expansion of iron, (approximately 0.0000122.) b is coefficient of the expansion of brass, (approximately 0.0000188.)

The function of the screw x' and the gradu- 75ated nut h is to adjust the pendulum-rod to the exactly correct length, so that the apparatus will keep correct time. As the nut is divided into ten spaces, each of which is sub- 80divided into ten degrees, it will be seen that a very fine and accurate adjustment of the pendulum may be readily obtained. 80

Having thus described our invention, we claim—

1. The combination of the local circuit, in- 85cluding the battery, the electro-magnet, the armature having the contact-points, and the vibrating arm having the contact-spring be- 90tween the contact-points and connected to the pendulum, and the line-circuit, including the electric clock or series of electric clocks, whereby when the pendulum swings in one direction the current from the battery flows through the local circuit, and when the pendu- 95lum swings in the contrary direction the current from the battery flows through the line-circuit, for the purposes set forth, substantially as described.

2. The combination, with the main circuit, including the electric clock, and local circuit, including the electro-magnet D, of the arma- 100ture having the contact-points connected with the main and local circuits, and the vibrating arm included in one circuit and playing be- 105tween the contact-points of the armature, to automatically make and break the main and local circuits alternately, for the purpose set forth, substantially as described.

3. The combination of the pendulum, the 110vibrating arm connected to the pendulum, the armature adapted to strike opposite sides of the vibrating arm to swing it and the pendu- 115lum, and the electro-magnet to attract the armature, substantially as described.

4. The combination of the pendulum, the 120vibrating arm connected thereto and having the spring W^2 , the armature having the arms or stops to strike opposite sides of the said 125spring alternately, and the electro-magnet to attract the armature, substantially as de- 130scribed.

5. The combination of the vertical iron rods having the cross-bar at their lower ends, the brass rod supported on the cross-bar, the fulerumed lever bearing on the brass rod, and the pendulum suspended from the said lever, substantially as described.

6. The combination of the plate C, the iron stirrup depending therefrom, the brass rod supported on the said stirrup, the lever connected to the brass rod and movable thereby, the screw x' in the said lever, the nut thereon, and the pendulum suspended from the screw, substantially as described.

7. The combination of the plate C, the iron stirrup depending therefrom, the brass rod

supported on the said stirrup, the lever connected to the brass rod and movable thereby, the screw x' , in the said lever, the graduated nut thereon, and the pendulum suspended from the said screw, substantially as described.

8. The combination of the supporting-screw x' with the spring-leaf suspended from the screw and having the head provided with the inclined open slot, and the pendulum having the slot at the upper end of its rod to receive the head, and the transverse pin to enter the open slot therein, substantially as described.

9. The combination of the supporting-screw

x' , the leaf pivoted to the lower end thereof and suspended therefrom, the pendulum suspended from the leaf, and the clamp to prevent lateral vibration of the leaf, substantially as described.

In testimony that we claim the foregoing as our own we have hereto affixed our signatures in presence of two witnesses.

JOHN JAMES ABELL.
CLARENCE BEN GIFFORD.
